A. J. LYNCH.

RAILROAD TIE.

APPLICATION FILED JUNE 27, 1914.

1,127,788.

Patented Feb. 9, 1915.

UNITED STATES PATENT OFFICE.

ANDREW J. LYNCH, OF NORTH YAKIMA, WASHINGTON.

RAILROAD-TIE.

1,127,788.

Specification of Letters Patent.

Patented Feb. 9, 1915.

Application filed June 27, 1914. Serial No. 847,660.

To all whom it may concern:

Be it known that I, ANDREW J. LYNCH, a citizen of the United States, residing at North Yakima, in the county of Yakima 5 and State of Washington, have invented a new and useful Railroad-Tie, of which the following is a specification.

The present invention appertains to railroad ties, and aims to provide a novel and 10 improved structure of that character.

The present invention contemplates the provision of a metallic tie of unique construction having peculiar means for receiving and holding the base flanges of the rails, 15 whereby the tie will have a long life, will withstand the strains under the conditions to which it is subjected, and will be thoroughly efficient in its use.

With the foregoing and other objects in 20 view which will appear as the description proceeds, the invention resides in the combination and arrangement of parts and in the details of construction hereinafter described and claimed, it being understood 25 that changes in the precise embodiment of the invention herein disclosed can be made within the scope of what is claimed without departing from the spirit of the invention.

The invention has been illustrated in its 30 preferred embodiment in the accompanying drawing, wherein:—

Figure 1 is a plan view of the improved tie with the rails engaged thereto. Fig. 2 is a longitudinal section of the tie taken on 35 the line 2—2 of Fig. 1. Figs. 3 and 4 are cross sectional views taken on the lines 3—3 and 4—4 respectively, of Fig. 1.

In carrying out the present invention, the tie is formed from a metallic plate 1 which 40 is bent into tubular form, the plate being bent transversely, and having its edge portions 2 disposed upwardly and bent inwardly to lie in a horizontal plane at the top of the tie. The edge portions 2 are 45 spaced apart to provide a longitudinal upper opening, and the said inturned edge portions 2 of the plate 1 are provided adjacent the ends of the ties with recesses 3 for receiving the base flanges 4 of the rails. 50 Those ends or recesses 3 nearest one end of the tie, are flat to form shoulders for the abutment of the corresponding edges of the base flanges 4, while the other ends of the recesses 3 are provided with undercut 55 grooves 6 receiving the other edges of the base flanges 4, and providing tongues or

keepers 7 overlapping the corresponding edge portions of the base flanges 4 to maintain them within the depressions or recesses 3.

The rail locking or securing means embodies an elongated plate or relatively wide bar 8 disposed within the tie immediately below the edge portions 2 thereof and having its end portions projecting beyond the rails 5. The locking bar 8 is provided with an upper median rib 9 disposed snugly between the edge portions 2 of the tie, and provided with recesses or depressions 10 complementing the recesses 3 and adapted to receive the base flanges 4 of the rails. Those ends of the recesses 10 adjacent the undercut grooves 6 of the recesses 3 are flat to provide shoulders, while the other ends of the recesses 10 are provided with undercut grooves 11 for receiving the corresponding edge portions of the base flanges 4, and providing keepers 12 adapted to engage or overlap the corresponding edge portions of the base flanges 4.

In order to drive or force the clamping bar longitudinally within the tie, to clamp the base flanges of the rails in place, the sides of the tie 1 are provided at one end thereof and directly below the inturned edge portions 2, with openings 13 through which is inserted and driven a tapered or wedge-like pin 14, which rests against the corresponding end of the bar 8, to force the bar toward the other end of the tie, as the pin 14 is driven home.

In use, to assemble the parts, supposing the same to be separated, after the tie 1 is properly embedded or planted in the road bed, and the locking bar 8 placed or inserted within the tie 1, the flanges 4 of the rails may have their proper edge portions inserted and engaged under the keepers 7, to permit the flanges to seat snugly within the depressions or recesses 3 of the tie. Then, by lifting the bar 8 upwardly against the edge portions 2 of the tie, to bring the rib 9 between the said edge portions, the recesses 10 may be made to receive the base flanges 4, with the tongues or keepers 12 disengaged from the base flanges when the bar 8 is moved toward that end of the tie having the openings 13. Then, by moving or sliding the bar 8 toward the other end, the tongues or keepers 12 may be slid over the flanges 4 of the rails, and finally by inserting and driving the pin 14 through the open-

ings 13, the locking bar may be forcibly driven toward the other end of the tie to clamp the base flanges of the rails between the oppositely arranged tongues or keepers 7 and 12. Thus, the base flanges of the rails are clamped and held within the recesses 3 and 10, and the rails will be firmly held in place notwithstanding the strains and conditions to which the rails and tie are subjected in use. The tie and rail-securing means will be substantial and efficient in use.

To detach the rails from the tie, it is merely necessary to withdraw the pin 14, so that the locking bar 8 may be moved longitudinally to disengage the tongues or keepers 12 from the base flanges of the rails in which event the rails may be lifted or withdrawn out of the recesses 3 of the tie, as well as from the recesses 10 of the bar 8.

The tubular form of the tie enables the same to be ballasted, if desired, and it is to be noted that the locking bar 8 fitting below the edge portions 2 of the tie, will be effectively locked against upward movement when the rails are secured or clamped in place. The other advantages and attributes of the present device will be obvious to those versed in the art, without further comment being necessary.

Having thus described the invention, what is claimed as new is:—

1. In a device of the character described, a tie comprising a transversely bent plate having its edge portions uppermost and bent inwardly, and a locking bar mounted between the said edge portions, the edge portions of the plate having keepers to engage over certain edge portions of the base flanges of the rails, and the said bar having keepers to engage over the other edge portions of the base flanges when the bar is moved longitudinally.

2. In a device of the character described, a tie comprising a transversely bent plate having its edge portions disposed uppermost and bent inwardly, said edge portions having recesses to receive the base flanges of the rails and having undercut grooves at

certain ends of the recesses to receive certain edge portions of the base flanges of the rails, and a locking bar slidably mounted between the said edge portions and having recesses complementing the aforesaid recesses for receiving the base flanges, the recesses of the locking bar having undercut grooves opposite the aforesaid undercut grooves to engage the other edge portions of the base flanges when the locking bar is moved longitudinally.

3. In a device of the character described, a tie comprising a transverse bent plate having its edge portions uppermost and bent inwardly, a locking bar disposed slidably below the said edge portions, the said edge portions having keepers to engage certain portions of the base flanges of the rails, and the locking bar having keepers between the said edge portions and engageable with the other edge portions of the base flanges.

4. In a device of the character described, a tie comprising a transversely bent plate having its edge portions uppermost and bent inwardly, the said edge portions having recesses to receive the base flanges of the rails and the recesses having undercut grooves at certain ends to receive certain edge portions of the base flanges, and a locking bar disposed immediately below and slidably engaging the said edge portions, the locking bar having an upper rib disposed snugly between the said edge portions, the rib having recesses complementing the aforesaid recesses to receive the base flanges, the said rib having undercut grooves at those ends of the recesses of the said rib which are remote from the aforesaid undercut grooves, to engage the other edge portions of the base flanges when the bar is moved longitudinally.

In testimony that I claim the foregoing as my own, I have hereto affixed my signature in the presence of two witnesses.

ANDREW J. LYNCH.

Witnesses:

MINNIE A. THOMPSON,
R. C. LYNCH.
